UNITED STATES PATENT OFFICE.

ALLAN C. GIRDWOOD, OF BALTIMORE, MARYLAND.

ATTACHMENT FOR GOLF CLUBS.

Application filed March 19, 1926. Serial No. 95,871.

This invention relates to games and has special reference to golf clubs.

The center of gravity of golf clubs varies in position from seven to fifteen inches up from the heel of the head. This variation occurs to some extent even in clubs for the same purpose and made by the same person or manufacturer. Consequently the user of a club, becoming accustomed to the balance of that particular club, is thrown off his play upon using a club with a different balance such as is caused by a variation in the position of the center of gravity.

One important object of the present invention is to provide an improved form of golf club having means whereby the center of gravity may be adjusted to suit the individual player.

A second important object of the invention is to provide an improved attachment for golf clubs whereby the center of gravity may be raised or lowered as desired by the player using the club.

It is well understood that, other things being equal, the more nearly the center of gravity can be brought to a low point the greater the centrifugal force developed in the swing of the club which materially aids in long drives. Also, by concentrating the weight towards the head the tendency will be to hit the ball in the center of the face rather than toward the toe, such concentration of weight also aiding to cause the head to travel in a plane so that cutting the head across the ball is prevented.

A third important object of the invention is to provide an improved attachment for golf club heads which aids in concentrating weight at a low point on the club.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of the lower portion of a golf club head showing the attachment in place.

Figure 2 is an enlarged section on the line 2-2 of Figure 1.

In the drawing it will be seen that the club shown has a head 10 from which a metal shank 11 extends of an angle, this shank being of less diameter adjacent the head and being taperingly enlarged upwardly to the point at which it joins the wooden shaft 12, this being the ordinary construction of such clubs.

The attachment consists of a heavy metal ring formed of two halves 13 having their ends provided with rabbeted overlapping portions 14 through which pass the set screws 15 which not only hold the two halves together but which bite into the material of the shank 11 when adjusted thereon so that the ring may be secured in any desired position on the shank. Obviously the interior of the ring is tapered to conform to the taper of the shank end, when used on the narrower part of the shank, may have an internal liner or shim 16.

By means of this attachment the center of gravity of the club may be adjusted within limits since the lower the position of the ring the lower will be the center of gravity of the club as a whole.

There has thus been provided a simple and efficient device of the kind described and for the purpose specified.

Having thus described the invention, what is claimed as new, is:

1. The combination with a golf club having a head and shank; of a weight ring slidably mounted on said shank to move toward and from the head, and means to hold the ring in adjusted position on the shank.

2. The combination with a golf club having a head and shank; of a ring slidably mounted on the shank to move toward and from the head, said ring consisting of arcuate sections provided at their ends with overlapping rabbets, and set screws passing through the overlapping rabbets and engaging the shank.

3. An attachment for golf clubs consisting of a ring formed of a plurality of arcuate sections having interengaging ends, and set screws passing through the interengaging ends to hold the parts of the ring together, said set screws being adapted to project inferiorly of the ring to engage the shank of a golf club head.

In testimony whereof I affix my signature.

ALLAN C. GIRDWOOD.
